United States Patent Office

Des. 215,321

Patented Sept. 23, 1969

215,321

CANDY DISH OR SIMILAR ARTICLE

Oscar Jacob, 453 S. Las Palmas Ave.,
Los Angeles, Calif. 90005

Filed Nov. 1, 1968, Ser. No. 14,267

Term of patent 7 years

Int. Cl. D7—01

U.S. Cl. D36—2

FIG. 1 is an elevational view of a candy dish or similar article showing my new design;

FIG. 2 is a right side elevational view; and

FIG. 3 is a top plan view.

I claim:

The ornamental design for candy dish or similar article, as shown.
